Primary Examiner—Cathron C Brooks*Assistant Examiner*—Barbara Fox(74) *Attorney, Agent, or Firm*—Boyle Fredrickson, S.C.(57) **CLAIM**

The ornamental design for a door wedge, as shown and described.

DESCRIPTION

FIG. 1 is an isometric view of a door wedge in accordance with the present invention;

FIG. 2 is a top plan view of the door wedge of FIG. 1;

FIG. 3 is a side elevational view of the door wedge of FIG. 1;

FIG. 4 is an end view of the door wedge of FIG. 1; and,

FIG. 5 is a bottom plan view of the door wedge of FIG. 1.

The broken lines shown in the drawings are for the purpose of illustrating unclaimed portions of the door wedge and form no part of the claimed design.
